UNITED STATES PATENT OFFICE.

GEORGE E. TYSON, OF READING, PENNSYLVANIA.

DESIGN FOR A LEVER FOR SASH-FASTENERS.

SPECIFICATION forming part of Design No. 32,817, dated June 12, 1900.

Application filed May 7, 1900. Serial No. 15,844. Term of patent 7 years.

To all whom it may concern:

Be it known that I, GEORGE E. TYSON, a citizen of the United States of America, and a resident of Reading, in the county of Berks and State of Pennsylvania, have invented and produced a certain new and original Design for a Lever for a Sash-Fastener, of which the following is a specification.

Figure 1 is a plan view of a lever, showing my new design. Fig. 2 is a side edge view, and Fig. 3 an end view, of the same.

As shown in the drawings, the leading features of my design consist of the imperforate plate *a*, having a rib *b* rising from the substantially-semicircular outer edge thereof, said rib terminating at one end in a bent

handle-piece *c* and at the other end gradually decreasing in height, as shown at *d*, and a cylindrical hub *e*, formed on the lower face of said plate *a* and having a reduced extension *f*, with flattened sides *g*, and a laterally-projecting flange *h* at the base of said reduced extension.

What I claim is—

The design for a lever for a sash-fastener as shown and described.

Signed by me at Reading, Pennsylvania, this 4th day of May, 1900.

GEO. E. TYSON.
